PIVOTED CLOSURE FOR DISPENSING
CONTAINERS

George H. Hawkins, Detroit, Mich.

Application November 6, 1947, Serial No. 784,397

3 Claims. (Cl. 222—553)

1

My invention relates to a new and useful improvement in a closure for dispensing containers which are adapted to hold loose particles, such as, tooth powder and the like. It is an object of the present invention to provide a closure for a container of this class which may be easily and quickly moved to open or closed position and which, when moved to open position, will uncover an outlet opening which is central to the container so that it becomes possible when the outlet opening is uncovered to empty the entire contents of the container.

Another object of the invention is the provision of a closure for a container of this class so constructed and arranged that it may be economically manufactured, durable, easily and quickly assembled, easily operated and highly efficient in use.

Other objects will appear hereinafter.

It is recognized that various modifications and changes may be made in the detail of structure illustrated without departing from the invention and it is intended that such shall be embraced within the scope of the claims which form a part hereof.

Forming a part of this specification are drawings in which,

Fig. 1 is a side elevational view of a container showing the invention applied with a part of the container broken away,

Fig. 2 is a top plan view of the container showing the invention applied and in closing position,

Fig. 3 is a top plan view of the container showing the invention applied with the closure in open position,

Fig. 4 is an enlarged view taken on line 4—4 of Fig. 2,

Fig. 5 is an enlarged sectional view taken on line 5—5 of Fig. 4,

Fig. 6 is a perspective view of the cap or closure used in the invention.

Fig. 7 is a fragmentary, top plan view illustrating a modified form,

Fig. 8 is a side elevational view of the modified form,

Fig. 9 is a sectional view taken on line 9—9 of Fig. 8, slightly enlarged.

In the drawings, I have indicated a container 1 adapted for receiving loose particles, such as, powder, salt, sugar or the like and provided with a top 8 extending centrally upwardly from which is a neck 9. Mounted on this neck 9 is a head 10. It is believed obvious that the head 10 may be made integral with the top 8 if desired or made integral with the neck 9, if desired. Formed in

this head 10 is a central opening 11 which is centralized relatively to the container 1. It will be noted that the head has a substantially semi-spherical portion or surface on the outer side. Formed integral with the head 10, and projecting outwardly therefrom, is a pair of spaced apart bosses 12 and 13. A cover or cap 14 of substantially semi-spherical construction is used and provided with an opening 15 through which the boss 12 is projected. The boss 12 is then up-set to provide the clinching portion 16 so that the semi-spherical cap 14 is thus rotatably mounted on the head 10 on the axis of the boss 12. This cap 14 is cut away, as at 18, and is provided along its marginal edges with the narrowed portion 17 so that the semi-spherical cap 14 may be easily rotated on the boss 12 as a pivot. When rotated into position so that a cut away portion engages the boss 13 at one side, the cap 14 will have covered the opening 11, as shown in Fig. 2. When rotated to the position in Fig. 3, the boss 13 will be engaged by the other side of the cut-out portion 18 and the opening 11 will be exposed or uncovered. It will be noted that the cap 14 rotates on an axis which is extended angularly to the axis of the opening 11 so that only a portion of the spherical surface of the head 10 is covered by the cap 14. It is also to be noted that the cap 14 nests on the head 10, thus forming a compact and attractive construction.

When the head 10 is being formed, which is preferably formed as a stamping, the bosses 12 and 13 may be punched outwardly at the same time, and when the cap 14 is formed as a stamping, the opening 15 and the cut-away portion 18 may be stamped in a single operation. It is but necessary then to mount the cap 14 so that the boss 12 projects therethrough and then produce the up-set portion 16, thus affording a very economical construction and one which is light and durable and possessed of the advantages which are believed apparent and enumerated herein.

In Figs. 7, Fig. 8, and Fig. 9, I have shown a slight modification in which the top 8a is provided with the upstanding neck 9a on which is mounted or formed the head 10a. Formed in the periphery of the head 10a is a circular groove 20, the plane of which is inclined to the axis of the head. Formed in the center of the head 10a is the central opening 11a. A cover or cap 14a is provided at its edges with the inwardly turned flange 21 which engages in the groove 20, the cap or head 14a being resilient so that the flange 21 may snap into the groove and, thus, the head or cap 14a, which is substantially semi-spherical, is swing-

able or rotatable on the head 10. Formed in the cap 14a is an opening 22 which, of course, is off center and which will register with the opening 11a when the cap 14a is swung or rotated to a certain position.

In all of the forms shown it will be noted that the cap or cover 14 or 14a is positioned on the head so that the axis of this cap or cover extends angularly to the longitudinal axis of the container. This is clearly obvious from an examination of Fig. 1. The opening 11 or 11a formed in the head of the container is centrally of the container so that it is in alignment with the central longitudinal axis of the container.

What I claim as new is:

1. A dispensing closure for a container, adapted for the reception of loose material, comprising: a head on said container of substantially semi-spherical formation and having an outlet opening formed centrally thereof; a pair of bosses projecting outwardly from said head in spaced apart relation and off-set from the center; a substantially semi-spherical closure for said opening having a portion cut away and provided with an opening for reception of one of said bosses, said boss having an up-set portion over said closure to provide a pivot, said closure being swingable into position for bringing said cut away portion out of and into registration with said opening for covering said opening and uncovering said opening the other of said bosses engaging said cut away portion for limiting swingable movements of said closure to open and closed positions.

2. A dispensing closure for a container, comprising: a head mounted on said container and serving as a closure therefor, and having a substantially spherical contour and provided with an opening formed centrally therethrough substantially centrally of said container and in alignment with the longitudinal axis thereof; a boss pressed

outwardly and forming a part of said head and spaced from said opening; a substantially semi-spherical closure for closing said opening in said head and mounted in nesting relation to said

5 head with its axis extended angularly to the longitudinal axis of said container and having an opening formed therethrough for reception of said boss, said boss forming a pivot for swinging of said closure to open and closing position relatively to said opening.

10 3. A dispensing closure for a container, comprising: a substantially semi-spherical head on said container serving as a closure therefor and having an opening formed therethrough communicating with the interior of said container and in alignment with the central longitudinal axis thereof; an outwardly projecting boss formed integral with said head and spaced from said opening; a substantially semi-spherical cover for 15 said head positioned thereon in nesting relation and having an opening formed therethrough for reception of said boss the axis of said cover extending angularly to the longitudinal axis of said container; an up-set portion on said boss for retaining said cover in position and providing a 20 pivot for said cover, said cover being swingable into position for closing said opening or for exposing the same.

GEORGE H. HAWKINS.
